APPARATUS FOR IMPREGNATING SOLID BODIES

Percy Huggins, Sale, England, assignor of one-half to Lancashire Dynamo & Crypto Limited, Manchester, England

Application June 8, 1949, Serial No. 97,793
In Great Britain June 8, 1948

4 Claims. (Cl. 118—64)

1

This invention relates to the impregnation of solid bodies, and has particular, though not exclusive, application to the impregnation of electrical windings for dynamo-electric machines and transformers, in connection with which it will be described.

Impregnation of windings is normally carried out by placing the work in an impregnating chamber, having at the bottom an inlet for the varnish or other impregnant, and near the top a connection with a pump whereby vacuum or pressure conditions may be induced in the chamber. The vacuum is used for drawing the impregnant into the chamber, and may also be used for additional purposes, such as assisting pre-drying of the work and evacuation of solvent from the impregnant after impregnation. After the work has stood in the varnish for a predetermined period the varnish is allowed to drain back into a stock tank, or is forced back by pressure. The work is then stoved.

It is an object of the present invention to reduce the time, fuel, and labour required for impregnation and to increase the degree of control thereof; a further object is to retard unwanted drainage of the impregnant from the work and thereby improve the efficiency of the impregnation.

According to the invention, a method of impregnating a solid body comprises immersing it in an impregnant for the requisite period, removing the bulk of the impregnant, and then subjecting the body to an upward blast of heated air.

After removal of the bulk of the impregnant, and prior to the application of the hot blast, the body may be subjected to a vacuum.

A proportion of the heated air, after passing over the body, may be re-heated and re-circulated.

The invention also includes apparatus for impregnating a solid body, comprising an impregnating chamber provided with a source of impregnant and means to induce conditions of pressure or vacuum, wherein circulating means are arranged to feed a blast of air through a heater into the chamber near the bottom thereof and to exhaust it from the top of the chamber.

The circulating means may be arranged to re-heat a proportion of the exhaust air and re-circulate it to the chamber.

The impregnating chamber and the circulating means may be connected by ducts having blanking means serving to seal the impregnating chamber at will.

2

Each of the ducts may include a telescopic connection mounted on one part of the duct and arranged to be coupled with the other part, and a sealing plate arranged to be secured to said other part when it is uncoupled from the telescopic connection.

Alternatively, the impregnating chamber may be provided with a pressure lid, for use during conditions of pressure, and with a coupling lid, arranged to replace the pressure lid and formed with ducting to couple the impregnating chamber with the circulating means.

The means serving to feed the blast of air into the impregnating chamber may include a vertical duct leading from the top to the neighbourhood of the bottom of said chamber and apertured at intervals throughout its length to permit part of the blast of air to be delivered to the upper and middle parts of said chamber. Two or more such vertical ducts may be provided at spaced intervals around the interior of the impregnating chamber and arranged for delivery of the blast of air.

A sump may be provided between the impregnating chamber and the source of impregnant, for the collection of used impregnant which has become undesirably viscous.

Two embodiments of the invention will be described with reference to the accompanying drawings, in which:

Figure 1 is a diagrammatic sectional elevation of one form of impregnating plant,

Figure 2 is a fragmentary diagrammatic view showing the blanking means in operation, and

Figure 3 is a fragmentary diagrammatic view of another form of impregnating plant having a coupling lid.

Referring to Figures 1 and 2, in one embodiment of the invention, for the impregnation of electrical windings, a cylindrical impregnating chamber 10 is employed, having a connection 11 at the bottom communicating with a sump 12, the function of which will be described hereinafter. A pipe 13 in which is located a valve 14 communicates with a stock tank 15 of varnish, and the chamber 10 has a connection 16 near the top coupled, through a valve 17, with an air pump (not shown), and a flanged upper edge 18 arranged to receive a pressure-tight lid 19 seating on a sealing ring 20. In addition, vertical ducts 21 extend down the inside of the chamber 10. Each duct has a flange 22 at its upper end, which is approximately level with the upper edge 18 of the chamber, and with its open lower end 23 terminating a short distance above the bottom

of the chamber 10. Just above said lower end, a platform 24 extends across the chamber to support the work, and is formed with perforations such as 25 so as to act as an air diffuser, as will be seen hereinafter. To assist varnish drainage and air diffusion, the perforations 25 may be formed by a very open grid on the top of which are welded closely spaced angle irons with vertices upwards. The vertical duct 21 is formed at intervals along its length with louvres 26.

Adjacent to the impregnating chamber 10 is a circulating system comprising an air inlet 27 to draw air from the atmosphere, a heater 28 to heat the air, and a circulating fan 29 to drive the heated air through a delivery duct 30 to the chamber 10. The duct 30 is provided with a pressure-tight telescopic section 31 which may either be extended, as shown in Figure 1, or retracted, as shown in Figure 2. In its extended position the telescopic section 31 is arranged to be secured to distributor 32 from which branch short ducts 32 leading through the lid 19 of the chamber 10 to the top of the vertical duct 21. When the telescopic section 31 is in its retracted position the outer end of the duct 32 may be blanked off by a sealing plate 33 secured thereto by a captive clamp (not shown).

The pressure lid 19 is formed with an exhaust duct 34 arranged to collect exhaust air from the top of the impregnating chamber 10 and deliver it to one end of a duct 35 from which there stem two branch ducts 36, 37. The duct 35 is provided with a pressure-tight telescopic section 38 similar to the section 31, and the duct 34 may be blanked off by a sealing plate 39 in the same manner as the duct 32 hereinbefore described. The branch duct 36 constitutes an exhaust flue to atmosphere, and is provided with an exhaust fan 40 at the base of stack 36a. The other branch duct 37 leads to the heater 28, and is formed with an aperture 27 which constitutes the previously mentioned fresh air inlet to the system. At the junction of the ducts 35, 36, 37 is a damper 41 which serves to open or close simultaneously the fresh air inlet 27 and exhaust flue 36, and at the same time to close or open the passage between the main exhaust duct 35 from the impregnating chamber 10 and the heater 28, so causing the air from the impregnating chamber 10 to be guided into the exhaust flue 36 to atmosphere, or into the heater 28, or in varying proportions into each, as may be desired.

The heater 28 may be of any suitable type, but preferably is of the direct fired gas type, with thermostatic control.

The sequence of operations is as follows: the work is placed in the impregnating chamber 10 on the perforated platform 24 and the pressure lid 19 is bolted on. The work may or may not have been pre-heated in the chamber 10. The need for this step depends on the nature of the impregnant, and with some types of varnish pre-heating is not only unnecessary, but indeed undesirable. If it is considered necessary, it can be carried out with the work in the chamber 10 by coupling the chamber with the circulating system, which is then run for the prescribed period with the heater 28 in operation. The ducts 32, 34 are then blanked off by the sealing plates 33, 39 as shown in Figure 2, so isolating the chamber 10 by means of the air pump acting through the pipe 16 and valve 17 from the circulating system. Vacuum is then formed in the chamber 10 and maintained for a sufficient period to extract air and moisture from the wind-

ings of the work. The valve 17 is then closed and the valve 14 to the stock tank 15 is then opened and the varnish is sucked up through the pipe 13 into the chamber 10 until the work is immersed. The valve 14 is then closed and the vacuum is broken as by admitting air through the pipe 16.

The work remains in the varnish for the prescribed period, and if desired pressure can be applied at this stage. The valve 14 to the stock tank 15 is then opened and the varnish is blown back or allowed to drain back into the stock tank.

It has been found that some of this is too thick to mix with the next upward flow of impregnant from the stock tank 15. Were provision not made to counteract its effect, it might accumulate in the pipe 13 and in time congest it. This is overcome, however, by the sump 12, which collects that portion of the impregnant which has increased in specific gravity during the impregnating and is decanted into the sump, while not impeding the flow of impregnant to and from between the chamber 10 and the stock tank 15. The sump 12 may be cleared periodically.

The sealing plates 33, 39 are then removed and the telescopic sections 31, 38 are coupled up to the ducts 32, 34. The air inlet damper 41 is fully opened, and is therefore simultaneously set for full exhaustion to atmosphere. The circulating fan 29 is started up and the system is run in this condition for a short time to clear it of solvent vapour or any other inflammable gaseous content.

The heater 28 is then put into operation and the damper 41 is moved so as partially to close the air inlet 27 and admit exhaust to the heater 28 for recirculation. The setting of the damper 41 permits any desired degree of recirculation to be obtained. The hot air blast is delivered down the vertical ducts 21 inside the chamber 10, and passes up through the perforations 25 of the platform 24 and so is diffused over the work. In addition, a proportion of the hot air blast passes out through the louvres 26 into the upper and middle parts of the chamber 10. This proportion is selected to suit the nature and size of the work being impregnated, and the number, size, location, and direction of the louvres 26 are chosen accordingly. In most instances very much under 50% of the hot air blast is required to be dispersed through the louvres. The turbulence caused thereby is beneficial in sweeping irregular surfaces with the hot air, and in minimizing the slight temperature gradient which inevitably exists between the bottom and the top of the chamber 10. By its upward movement the hot air arrests the downward draining of the varnish and permits of more efficient impregnation, which is further improved by the absence of solvent-laden air, the presence of which is undesirable during curing.

Any inflammable solvents released from the work are carried in the exhaust 34, 35 partly to the atmosphere and partly to the heater 28 (depending on the degree of recirculation for which the damper 41 is set) and such solvents as are carried to the heater 28 are there burnt, if the heater is of the direct fired type. The hot air blast is maintained for the time necessary to cure the varnish. The circulating fan 29 and the heater 28 are then shut down and the lid 19 and the work are removed.

In another embodiment of the invention, part of which is illustrated diagrammatically in Figure 3, and which embodies only one vertical duct

21 the impregnating chamber 10 is the same as before, but instead of having a lid 19 it has the usual type of pressure-tight lid (not shown) which has no ducts communicating with it, and which seats on the flanges 18. In addition it has a second lid 42, termed the coupling lid, which is arranged to be secured to the top of the chamber 10 instead of the pressure lid. For this purpose the chamber and both the lids are formed with co-operating means of known type such as locating studs and apertures mating therewith, to ensure the rapid and easy substitution of one lid for another.

The coupling lid 42 is formed with a duct 43 arranged to register on the one hand with the vertical duct 21 extending within the impregnating chamber 10, and on the other hand with the delivery duct 30^a in the circulating system. The coupling lid is formed with another duct 44 arranged to register with the duct 35^a. Suitable pressure-tight flanged connections are provided to permit of rapid attachment of the coupling lid 42 to these ducts. The remainder of the circulating system is the same as that shown in Figure 1.

If desired, the coupling lid 42 may incorporate a pressure release door or other device to safeguard against explosion when the impregnant contains volatile inflammable constituents.

The incorporation in the removable coupling lid of the ducts to put the impregnating chamber 10 in communication with the circulating system obviates the necessity of cutting openings in the chamber, and enables an existing chamber to be rapidly converted without being taken out of commission. Moreover, it renders unnecessary the provision of valves in the circulating ducts to seal off the air blast equipment from the chamber when vacuum or pressure is applied to the latter. Further, it is impossible to apply air blast heating to the chamber until the coupling lid is in position. This is an important advantage when volatile inflammable impregnants are employed, and pressure release means are provided in the coupling lid. By the use of this separate lid the provision of a safety interlock is obviated.

By the above methods there is accomplished an economy in fuel, owing to the recirculation of the hot air, whereby the heater has only to make up the heat lost by the air during its passage round the system. The work is more quickly heated by the hot blast, and therefore the stoving time is reduced. There is also achieved an economy in labour, due to the whole process being accomplished in one chamber without removal of the work therefrom, and under conditions of greater control than have heretofore been possible.

I claim:

1. Apparatus for impregnating a solid body

comprising an impregnating chamber, tank means for holding a supply of liquid impregnant, means connecting said chamber and said tank means for conveying sufficient impregnant into said chamber to immerse the solid body and for withdrawing and returning excess impregnant to said tank means, circulating means, ducts connecting said circulating means with the top and bottom of said chamber, a telescopic connection in each duct, whereby when the connections are uncoupled sealing plates may be secured to the parts of the ducts connected to the chamber to close off the circulating means from said chamber, a heater connected to said circulating means, and said circulating means feeding a blast of air through said heater into said chamber near the bottom thereof, and exhausting said air from the top of said chamber.

2. Apparatus for impregnating a solid body as in claim 1, said circulating means further comprising a vertical duct in said chamber extending from the top thereof to adjacent the bottom of said chamber, and apertures spaced along the length of said vertical duct for delivering part of the blast of air to the upper and middle portions of said chamber.

3. Apparatus for impregnating a solid body as in claim 1, said circulating means further comprising at least two vertical ducts spaced apart in said chamber for the delivery of the air blast into said chamber.

4. Apparatus for impregnating a solid body as in claim 3, further comprising said vertical ducts extending from the top to adjacent the bottom of said chamber, and apertures spaced along the length of each vertical duct for delivering part of the blast of air to the upper and middle portions of said chamber.

PERCY HUGGINS.
